UNITED STATES PATENT OFFICE

2,297,002

PRESSURE CONTAINER

Donald E. Larson, Chicago, Ill., assignor to Chicago Bridge & Iron Company, a corporation of Illinois

Application February 8, 1941, Serial No. 378,081

6 Claims. (Cl. 220—1)

This invention relates to improvements in pressure containers and more especially to such a container particularly adapted for storing products of high value and relatively low volatility such as aviation gasoline, naphtha and the like.

Among the features of my invention is a pressure vessel which can be built economically in large units. One of the things that adds greatly to the cost of any large vessel designed for a low working pressure is the necessity of strengthening it to withstand the full working gas pressure when it contains little or no liquid. In containers where this is taken care of by curved bottom plates, circular girders, or inclined tension members, or combinations of the same, the construction becomes quite expensive.

I have found that if enough weight can be hung on the shell at the equator and on the roof at the intersections or cusps, the columns can be made vertical and the bottom substantially flat, thus effecting an appreciable saving in cost. In the following specification I have shown how this can be accomplished in several practical ways.

In those forms of device embodying the features of my invention illustrated in the accompanying drawings, Fig. 1 is a top plan view; Fig. 2 is a vertical sectional view; Figs. 3, 4 and 5 are diagrammatic views similar to Fig. 2 showing modified forms; Fig. 6 is a view showing general relations and computations; and Figs. 7, 8, 9 and 10 are diagrammatic views similar to Fig. 2 showing modified forms.

As shown in the drawings, the container of Figs. 1 and 2 is circular in horizontal cross-section and provided with a noded roof 10, cylindrical shell 11 and vertical columns 12. The central portion of the bottom as indicated by 13 is flat. The outer periphery of the bottom is in the form of a trough 13a. 14 indicates a dam at the inner edge of the trough 13a. The central portion of the top as indicated by 10a is dome shaped and the outer periphery is noded as indicated by 10b. The line of intersection of the portion 10b with the periphery of the central dome 10a, or cusp, is indicated by 15.

16 indicates the inlet pipe so that all incoming liquid is directed into the outer trough 13a. It is confined there by the dam 14 which serves both as a retainer and as a girder for transmitting load to the tension ties 12a in the outer post circle. After the trough has become full, the liquid flows over the dam 14 and thereafter the entire tank is filled to the normal maximum level which for example may be the line 15.

When the tank is empty it is designed to operate at a pressure of say $\frac{1}{4}$ pound per square inch

which is not great enough to cause any part of the structure to lift off of the foundation. After the trough 13a has been filled to the top of the dam 14, the vessel can operate at full working pressure throughout the remainder of its capacity range.

For example, the full working pressure may be 1 pound. In order to insure the presence of liquid in the trough 13a before permitting full working pressure, the auxiliary pressure vent 17 is provided. It is not necessary to show the details of this vent. It will suffice to say that it is connected to the interior of the tank by the pipe 18, the lower end 18a of which is a short distance below the upper edge of the dam 14. The valve 17 is set to vent at say $\frac{1}{4}$ pound per square inch pressure. Consequently, whenever there is no liquid in the pipe 18, the tank will vent at $\frac{1}{4}$ pound. Therefore, the tank will vent at this pressure until the trough 13a is filled when liquid will enter the pipe 18 through the lower end 18a to shut off the vent 17. 19 is a regular or main vent which has a pressure valve adapted to vent at the full working pressure which may, for example, be 1 pound per square inch. 20 indicates a vacuum valve set to vent inwardly at any desired negative internal pressure. For example, this valve may vent whenever the internal pressure becomes 1 ounce or more below atmospheric pressure.

The average depth of liquid in the trough 13a required to develop the full working pressure is determined by the following considerations. The weight of liquid in the trough plus the force of the specified working pressure acting downwardly on its surface must equal the product of the working pressure and the cross-sectional area of the tank. The low point of the trough must be so located that the weight of the liquid in the trough will be distributed between the shell and the outer circle ties in the correct proportion to balance the uplift at these points caused by the gas pressure acting on the roof.

In Fig. 6 I have shown the method of computing dimensions and proportions. In this drawing

r = tank radius in feet.

x = distance from center line to cusp in feet.

G = working gas pressure in pounds per square foot.

50 V_A = uplift at shell in pounds per foot.

V_C = uplift at cusp in pounds per foot.

H = height of liquid to balance uplift in feet.

z = distance from center line to trough bottom.

55 w = weight of liquid in pounds per cubic foot.

As an example it may be assumed that it is desired to build an 80,000 barrel tank with an over-

all diameter of 120 feet and a height of 40 feet with a working pressure of 216 pounds per square foot for holding liquid weighing 45 pounds per cubic foot. In such a structure, and referring to Fig. 6, if $x=40$ feet and $r=60$ feet, then

$$V_A = \frac{G}{2r}(r^2 - x^2)$$

$$V_A = \frac{216}{120}(3600 - 1600) = 3,600 \text{ pounds per foot}$$

$$V_c = \frac{Gx}{2}$$

$$V_c = \frac{216 \times 40}{2} = 4,320 \text{ pounds per foot}$$

$$H = \frac{Gx^2}{w(r^2 - x^2)}$$

$$H = \frac{216 \times 1600}{45(3600 - 1600)} = 3.84 \text{ feet, average depth of liquid in trough}$$

$$Z = \frac{x}{r}\sqrt{2r^2 - x^2}$$

$$Z = \frac{40}{60}\sqrt{7200 - 1600} = 49.8 \text{ feet from center line to bottom of trough}$$

It is to be noted that when

$$x = 0.68r, z = \frac{r+x}{2}$$

20a indicates the outlet pipe. Liquid is withdrawn from the center portion thus insuring that the outer trough remains full until the last of the liquid is removed.

An 80,000 barrel 1½ pound pressure tank, 120 feet in diameter, as described above, would require about 4 feet of gasoline in the outer trough or about 4,500 barrels to develop the full working pressure. The tank would operate as a ¼ pound pressure tank from 0 capacity to 4,500 barrels and have a 1½ pound pressure tank from 4,500 barrels to 80,000 barrels. A tank of this type has the distinct advantages that the gauging problem is simplified and all of the stresses are statically determined. About 70% of the weight of the tank is plain tank construction. No trusses or other highly fabricated parts are required. A distinct saving in fabrication and erection costs is effected.

It will be seen that the liquid confined in the outer trough serves to counterbalance the uplift due to gas pressure.

In the device of Figs. 1 and 2 the bottom of the outer trough is dished or curved downwardly. This trough could also be made flat as shown in Figs. 3 and 5 by merely extending the central portion of the flat bottom. In such cases, however, the bottom of the trough should be stiffened by radial trusses or girders as indicated by 330 and 530. In these views the dam or retainer plate corresponding to 14 in Fig. 2 is indicated by 314 and 514, respectively, and the bottom by 313 and 513. The extension of the flat bottom forming the flat bottom of the trough is correspondingly indicated by 313a and 513a.

In the device of Figs. 1 and 2 the side wall or shell of the tank is cylindrical. This construction is also employed in the device of Fig. 3 where such side wall is indicated by 311. In the devices of Figs. 4 and 5, however, the side wall as indicated by 411 and 511, respectively, is curved from the top entirely to the bottom. In the device of Fig. 4 this construction is shown in combination with a truss, the bottom of which is curved or dished as indicated by 413a the same as the trough of the device of Fig. 2.

It will be seen that in each case the top of the

tank has a central domed portion surrounded by a domed or upwardly curved peripheral portion over the peripheral trough in the bottom. The central domed portion of the roof is joined to the domed peripheral portion by the cusp 15, 315, 415 or 515. In each case the weight of liquid in the peripheral trough at the bottom serves to exert a downward pull at the periphery of the central domed portion of the roof through the posts or tension members 12a, 312a, 412a, or 512a, and also exerts a downward pull on the equator of the tank; that is the shell or side walls 11, 311, 411, or 511.

In Figs. 7, 8, 9 and 10 I have shown diagrammatically other means for imposing a downward pull on the side wall of the tank to counterbalance, at least partially, upward gas pressure within the tank. This downward pull on the side wall is transmitted to the periphery of the central domed portion. For example, in these figures the central domed portion is indicated by 710a, 810a, 910a and 110a, respectively. The side walls are indicated by 711, 811, 911 and 1011, respectively. As shown in Fig. 7, tension members 711a are provided at intervals around the tank with their upper ends attached to the side wall and their lower ends anchored in a concrete ring 713a. The construction of Fig. 8 is similar except that the side wall itself is continued downwardly as indicated by 811a to the ground level where it is anchored by means of the anchors 850 to the concrete ring 813a. In the device of Fig. 9 triangular plates 911a fasten the side wall to the torus 950 suitably weighted with concrete 951 or other appropriate material. In the device of Fig. 10 the side wall is anchored by means of the hollow torus 1011a filled with suitable liquid 1051.

The invention is particularly applicable in connection with a pressure container having a flat bottom. In a container of this kind, internal pressure tends to bend the edge of a flat bottom upwardly. This tendency is caused by the connection of the periphery of the roof to the edge of the bottom either through the side wall of the container or other tension members. The upward pressure on the roof operating through the side wall or these other tension members tends to bend or curve the edge of a flat bottom upwardly. In the practice of my invention I provide a trough attached to the periphery of the roof, with liquid in it, the weight of the liquid serving to counteract or counterbalance this upward pull and thus prevent the edge of the flat bottom from curving or bending upwardly. In the construction shown in Fig. 2 it will be seen that the trough 13a is connected to the periphery of the roof by both the tension members 12a and the side wall 11.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as permissible, in view of the prior art.

What I claim as new, and desire to secure by Letters Patent, is:

1. In combination with a pressure container having a flat bottom and domed top, a peripheral trough attached to the periphery of the top and communicating with the interior of the container, said attachment joining the trough to the periphery of the top in supporting relation with

respect to the top so that the weight of the trough with liquid therein tends to prevent upward movement of the periphery of the top from internal pressure in the container, said trough being supported by means other than said attachment to the periphery of the top when there is no internal pressure in the container, and liquid in the trough, the weight of said liquid serving to prevent upward bending of the periphery of the bottom from internal pressure.

2. In combination with a pressure container having a flat bottom and domed top, a peripheral trough outside of the periphery of the bottom and attached to the periphery of the top and communicating with the interior of the container, said attachment joining the trough to the periphery of the top in supporting relation with respect to the top so that the weight of the trough with liquid therein tends to prevent upward movement of the periphery of the top from internal pressure in the container, said trough being supported by means other than said attachment to the periphery of the top when there is no internal pressure in the container, and liquid in the trough, the weight of said liquid serving to prevent upward

bending of the periphery of the bottom from internal pressure.

3. A container as claimed in claim 1 in which the inner edge of the trough is attached to the periphery of the top by tension members and in which the outer edge of the trough is attached to the periphery of the top by the side wall of the tank and an outer peripheral top portion.

4. A container as claimed in claim 1 in which the inner edge of the trough is attached to the periphery of the top by tension members and in which the outer edge of the trough is attached to the periphery of the top by the side wall of the tank and an outer peripheral top portion, said outer peripheral top portion joining the main top portion by a cusp.

5. A container as claimed in claim 1 with an inlet pipe leading to the trough and an outlet pipe leading from the bottom of the tank inside the inner circumference of the trough.

6. A container as claimed in claim 2 with an inlet pipe leading to the trough and an outlet pipe leading from the bottom of the tank inside the inner circumference of the trough.

DONALD E. LARSON.
